CLAIM

The ornamental design for a power semiconductor module, as shown and described.

DESCRIPTION

FIG. 1 is a front, top and right side perspective view of a power semiconductor module showing our new design;

FIG. 2 is a front view thereof;

FIG. 3 is a rear view thereof;

FIG. 4 is a top plan view thereof;

FIG. 5 is an enlarged right side view thereof; and,

FIG. 6 is an enlarged left side view thereof.

The broken lines illustrate portions of the power semiconductor module that form no part of the claimed design.
